1 Claim

ABSTRACT OF THE DISCLOSURE

Apparatus for protectively covering the blades of a conventional electrical plug and locking the covering thereto in a manner to prevent dangerous insertion by a child into a standard outlet.

One of the main objects of the invention is to provide a simple and quickly attachable locking or latching cover to the open blades of an electrical plug to prevent dangerous outlet insertion by a child.

Another object of the invention is in the provision of a safety cover for electrical plug blades that prevents outlet insertion until unlocked or unlatched therefrom.

Yet another object of the invention is to provide a metal strap for the open blades that is padlocked thereto.

The fundamental theory of the present invention is to provide a simple, easily attachable and detachable cover for the open blades of an electrical plug and locking it thereto so that a child cannot possibly be injured by attempted insertion into the conventional electrical outlet. Small children playing on the floor or otherwise are constantly endangered by attempts to insert electrical plugs which operation they have seen their elders safely accomplish. The number of accidents from this simple cause is tremendous.

Applicant has provided a simple, inexpensive and easily attachable device that absolutely prevents any possibility of child injury. The playful youngster cannot make a dangerous connection no matter what position his or her fumbling hands assume.

These and other objects and advantages of the present invention will become apparent to those skilled in the art upon consideration of the following detailed description of the preferred embodiment thereof, reference being made to the accompanying drawings, herewith wherein:

FIG. 1 is an elevational view showing the blades in safely protected position;

FIG. 2 is an enlarged perspective view of the blade attaching pin;

FIG. 3 is an enlarged perspective view of the blade safety strap; and

2

FIG. 4 is a view similar to FIG. 1 with certain elements shown in section.

The drawings disclose a preferred embodiment of the invention but the metal cap might well be changed and the padlock could be a powerful latching means that would require adult operation.

A conventional electrical plug 10 has the projecting open blades 12 that are normally instantly insertable in the standard outlet, not shown. It is desired to quickly and easily lock or latch a metal strap 14 over the blade tips of the plug. The strap 14 surrounds the blades 12 and has a laterally projecting arm 16. The blade overlapping sides of the strap 14 are apertured at 18 to receive a lock pin 20 having an exterior O-ring 22. A conventional padlock is looped through the ring 22 and an opening 24 in the arm 16 to provide a secure metal or otherwise strap safety cover for the blades and prevent their dangerous insertion into a conventional electrical outlet by a child in playful adult copying mood.

The operation of the device is so simple as to obviate any further explanation.

While we have described in considerable detail what we believe to be the preferred form of our invention, it will be understood by those skilled in the art that various changes may be made in the shape and arrangement of the several parts.

We claim:

1. A quick detachable safety cover for apertured blades of conventional electrical service plugs, comprising:
a protective U-shaped strap covering the open plug blades;
said strap including two arms having holes which are aligned with the apertures in said blades when said strap covers said blades;
an apertured projection extending laterally from the end of one of said arms;
a pin with an eye at one end and adapted to be extended through the holes in said arms and the apertures in said blades to unite said strap to said blades in covering relation therewith and locate said eye in alignment with the aperture in said projection; and
optionally attachable locking means extending through said eye and said projection aperture to prevent the withdrawal of said pin from said strap.
